UNITED STATES PATENT OFFICE.

BERNARD E. FRANKE, OF BALTIMORE, MARYLAND, ASSIGNOR TO THE GEORGE FRANKE SONS COMPANY, A CORPORATION OF MARYLAND.

TINSEL REFLECTOR.

REISSUED

Application filed April 6, 1923. Serial No. 630,204.

To all whom it may concern:

Be it known that I, BERNARD E. FRANKE, a citizen of the United States of America, residing in the city of Baltimore, State of Maryland, have invented certain new and useful Improvements in Tinsel Reflectors, of which the following is a specification.

The present invention relates to a tinsel reflector for use on Christmas trees. The reflector consists of a mat of tinsel strips radiating from a central point near which point a small electric light of the kind ordinarily used for the decoration of Christmas trees is placed.

As the tinsel strips constituting the reflecting materials are of metal, usually soft, noncorrosive, cheap, easily worked alloy which is apt to be a good conductor of electricity, the use of the tinsel in the immediate vicinity of the sockets causes short-circuiting and immediate burning of the fuse so that the lights are, in many instances, extinguished almost as soon as the current is turned on.

For this reason, the applicant who is a manufacturer of such ornaments, after considerable experimentation with these reflectors, was unable to make them commercially desirable until further improvements, as herein described, were devised.

It is of importance to note that reflectors of this type, on account of the fragility of the material, are difficult to produce in such form that they may be supported at the center on a light socket, as described, so that they will retain their position in the scheme of decoration with a reasonable degree of permanency.

To meet the difficulties thus recited, the inventor has devised and provided a central support which engages the inner end portions of all the radiating tinsel strips and which also engages the light socket supporting the tinsel strips on the light socket or bulb shank, insulating them from the socket and from the shank of the light bulb. The supporting member is centrally apertured to pass the bulb shank and is of insulating material having a peripherally arranged pocket to receive the inner ends of the radiating tinsel strips.

Usually the supporting member consists of a double washer, i. e. two centrally apertured discs of fibrous material, preferably having insulating properties, the same being

secured together with the central apertures in registration, the radiating tinsel members having their inner ends disposed between the outer edge portions of the two discs, and held between the discs, preferably by a suitable adhesive which also holds the discs together.

In the accompanying drawings, I have illustrated a reflector lamp and lamp socket constructed and arranged in accordance with my invention.

In the drawings:

Fig. 1 is a sectional elevation showing a reflector, light and socket constructed and arranged in accordance with my invention, the section being taken on a diametrical line and the light and the socket being shown in elevation; for convenience of illustration, the parts are turned up slightly in perspective.

Fig. 2 is a view similar to Fig. 1 except that the outer ends of the tinsel members are broken away and that the light and socket are not shown.

Fig. 3 is a view of the reflector without the light and socket, the same being taken in the direction of the axis and substantially at right angles to Fig. 2.

Referring to the drawings by numerals each of which is used to indicate the same or similar parts in the different figures:

The reflector 1 is composed of radiating metallic tinsel strips; 2 preferably of a soft, cheap, non-corrosive metal. The tinsel strips are held at their inner ends in a suitable support 4, preferably of fibrous material. This, as shown, is circular, i. e. in the form of a disc, and is formed with a peripherally extending pocket, 6, to receive the inner ends of the tinsel strips to which they are held to the best advantage by adhesive.

The central support 4 is in the form of the invention shown and preferably built up of a plurality of washers or discs, 7, of fibrous or other suitable non-conducting material apertured at 8 and fastened together with the apertures in registration, the parts being secured by means of adhesive or in any other suitable manner. The support is thus centrally apertured, the apertured portion is duly insulated and the tinsel-reflecting members are supported in a radial position in relation to the light bulb and back of the same, the intended assemblage of the ap-

paratus, being that shank 10 of the bulb 11, is passed through the aperture 8 and seated in the socket 12, the front face 13 of the socket serving to position the reflector, supporting member 4, which rests on the socket, which socket and bulb shank are thus insulated from the metallic tinsel.

I have thus described specifically a single embodiment of my invention in order that 10 the nature and the operation of the same may be fully understood, however, the specific terms herein are used descriptively rather than in a limiting sense, the scope of the invention being defined in the claims.

15 What I claim and desire to secure by Letters Patent is:

1. The combination with a light bulb and socket of a reflector composed of radiating tinsel and a central holder for the tinsel 20 consisting of a disc having a central aperture to pass the shank of the bulb.

2. The combination with a light bulb and socket of a reflector composed of radiating tinsel and a central holder for the tinsel 25 consisting of a disc having a central aperture to pass the shank of the bulb, and

adapted to rest against the front face of the socket.

3. An ornamental reflector for decorating Christmas trees consisting of a mat of radiating tinsel members and a central holder therefor composed of a plurality of sheets of non-conducting material, part of said sheets being on each side of the tinsel, said holder being apertured near the center of 30 the reflector.

4. A Christmas tree ornament consisting of a reflector composed of a mat of tinsel strips so arranged that the tinsel members radiate substantially from a single center, 40 means for holding and supporting the inner ends of said tinsel members, consisting of sheets of fibrous material secured together and to said tinsel members and apertured near the center of the reflector to receive 45 and pass the shank of a light bulb.

Signed by me at Baltimore, Maryland,
this 4th day of April, 1923.

BERNARD E. FRANKE.
